PORTRABLE DRILL RIG

Filed May 22, 1935

UNITED STATES PATENT OFFICE

2,044,878

PORTABLE DRILL RIG

John C. Curtis, Garfield Heights, Ohio, assignor
to The Cleveland Rock Drill Company, Cleve-
land, Ohio, a corporation of Ohio

Application May 22, 1935, Serial No. 22,806

12 Claims. (Cl. 255—51)

This invention relates broadly to rock drills, but more particularly to a portable supporting and guiding apparatus therefor.

One object of this invention is to produce an improved rock drill supporting and guiding apparatus.

Another object of this invention is to produce a rock drill supporting frame pivotally connected to a carrying frame with a simple and efficient mechanism operable for causing the pivotal movement of the former relative to the latter.

Another object of this invention is to produce a drilling apparatus including a carrying frame having a rock drill supporting frame slidably and pivotally mounted thereon, with a mechanism slidable with the supporting frame and operable for causing the pivotal movement of the latter.

Other objects and advantages more or less ancillary to the foregoing and the manner in which the various objects are attained reside in the specific construction and aggroupment of the elements peculiar to this structure, in the claims of which there are assembled certain specific combinations of parts and specific constructions indicative of the scope and spirit of the invention.

In the drawing which illustrates the invention.

Fig. 1 is a side elevational view of the entire apparatus illustrating the drill supporting frame in one position.

Fig. 2 is a view similar to Fig. 1, illustrating the drill supporting frame in another position.

Fig. 3 is a top plan view of the assembly shown in Fig. 2.

Fig. 4 is an enlarged cross sectional view taken in a plane indicated by line 4—4 in Fig. 1.

Fig. 5 is an enlarged cross sectional view taken in a plane indicated by line 5—5 in Fig. 3.

Referring to the drawing in which like symbols designate corresponding parts throughout the several views, 10 represents a substantially U-shaped carrying frame made of tubular elements, and having brackets 11 secured to the end portion of the side arms thereof, each of the brackets being adapted to receive a supporting wheel 12.

The cross arm 13 of the carrying frame has secured thereto a bracket 14 adapted to pivotally receive a caster wheel 15.

Slidably mounted on each of the side arms of the carrying frame 10, there is a housing 16 formed with an arcuated seat or stationary jaw 17. To the housing 16 is pivotally secured by a pin 18, a jaw 19, which is disposed in opposition to the jaw 17 to form an opening therebetween adapted to receive the side arm of the frame 10. Operatively associated with the jaws 17 and 19,

there is a bolt 20 carrying a nut 21 by which the jaws may be clamped to the side arms of the frame for securing the housing 16 against slidable movement relatively thereto. Above the jaws 17 and 19, each of the housings 16 is provided with a tapered or conical socket 22. Rotatably mounted within the conical counterbore 22, there is a correspondingly shaped and centrally apertured member 23 having one end portion of the side arms of a substantially U-shaped supporting frame 24 welded thereto, affording thereby a pivotal and slidable connection between the carrying frame 10 and supporting frame 24. Disposed between the two housings 16, there is a cross bar 25 having the end portions thereof reduced as at 26 to form a shoulder 27 in abutting engagement with the members 23, the reduced portion 26 extending through the latter and the housing 16 to receive a nut 28 by which the members 23 may be clamped within their respective socket 22 against rotation relatively thereto. One of the housings 16 is provided with an upwardly extending projection 29 having a relatively small casing 30 pivotally secured to the free end portion thereof by a nut 31. This casing is formed with a cylindrical flat bottom bore 32 having a worm gear 33 rotatable therein, and provided with longitudinally disposed bore 34 adapted to receive the shank 35 of a screw 36. This shank is locked against rotation relative to the gear 33 by a key 37, and has the outer end portion thereof extending through the casing 30 to receive a nut 38, by which the screw is locked against longitudinal movement relative to the casing 30. Transversely disposed with respect to the bore 32, the casing 30 is formed with a relatively smaller bore 39 having a worm 40 rotatable therein in operative engagement with the teeth of the worm gear 33. This worm has one square end portion protruding from the casing 30 to receive a crank handle 41 by which the worm may be rotated. The screw 36 is rotatably mounted through a stationary nut 42, rigidly secured within one end portion of a tube 43. The other end of the tube 43 is pivotally connected to 45 the upper portion of one of the side arms of the frame 24 by a suitable connection 44.

Pivotedly secured to the supporting frame 24 by a connection 45, there is a drilling mechanism comprising an elongated frame 46 having a feeding 50 mechanism contained therein and capable of imparting feeding motion to a rock drill 47, which is slidably mounted on the elongated frame 46.

In the operation of the apparatus, when it is desired to slide the drill supporting frame 24 on 55

the carrying frame 10, the nuts 21 may be loosened, thus loosening the jaws 17 and 19 of the housings 16, and permitting the slidable movement of the latter on the side arms of the carrying frame 10. In this instance, the jack mechanism being carried by one of the housings 16 and the supporting frame 24, will slide with the latter. When it is desired to cause the pivotal movement of the supporting frame, the nuts 28 may be loosened, thus permitting the rotation of the members 23 relative to the conical counterbores or sockets 22. By operating the crank handle 41, rotation may be imparted to the screw 36 due to the rotation of the worm 40 and worm gear 33, thus causing the longitudinal movement of the screw 36 into or out of the tube 43 and the consequential upward or downward pivotal movement of the supporting frame 24.

From the foregoing, it will be seen that due to the novel method of securing the jacking mechanism to one of the connections between the frames 10 and 24, the jacking mechanism is slidable with the latter and consequently is always in operable position irrespective of the slidable movement of the drill supporting frame.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

35 I claim:

1. In a portable drill rig, the combination of a substantially U-shaped carrying frame, connections slidably carried by the side arms of said frame, a substantially U-shaped tool supporting frame pivotally and slidably secured to said carrying frame by said connections, and a mechanism carried by one of said connections for slidable movement therewith and including a screw threaded element pivotally connected to said tool supporting frame and operable for causing the pivotal movement of the latter relative to said carrying frame.

2. In a portable drill rig, the combination of a carrying frame, a substantially U-shaped tool supporting frame, connections carried by said carrying frame, each of said connections comprising a socket member slidable on said carrying frame having a correspondingly shaped element rotatable therein, each of said elements constituting the end portion of one side arm of said supporting frame, and a mechanism carried by one of said socket members for slidable movement therewith and comprising a screw threaded element operatively associated with said supporting frame and operable for imparting pivotal movement thereto.

3. In a portable drill rig, the combination of a carrying frame including two side members disposed in parallel alignment, a connection slidably mounted on each of said side members, a tool supporting frame connected by said connections to said carrying frame for slidable and pivotal movement between said side members, a mechanism carried by one of said connections for slidable movement therewith, said mechanism including a screw threaded element operatively connected to said supporting frame for imparting pivotal movement thereto, and means included in said connections for locking said supporting frame and consequently said mechanism against slidable movement relative to said carrying frame.

4. In a portable drill rig, the combination of a carrying frame including two side members disposed in parallel alignment, a connecting member slidably mounted on each of said side members, a tool supporting frame carried by said connecting members for slidable movement therewith, a bearing within each of said connecting members by which said supporting frame is pivotally connected to said carrying frame, and a mechanism pivotally carried by one of said connecting members for slidable movement therewith, said mechanism including telescopically mounted elements one associated with said supporting frame and operable for imparting pivotal movement thereto irrespective of the sliding movement thereof. 10

5. In a portable drill rig, the combination of a carrying frame including two side members, a connection slidably mounted on each of said side members, a tool supporting frame including two side elements, one end of each said side elements 20 being slidably and pivotally connected by said connections to said side members, and a mechanism associated with said tool supporting frame operable for imparting pivotal movement thereto, said mechanism being carried by one of said connections for slidable movement therewith relative to said carrying frame.

6. In a portable drill rig, the combination of a carrying frame, bearings carried by said frame, a substantially U-shaped tool supporting member 30 pivotally connected by said bearings to said carrying frame, a mechanism carried by one of said bearings including telescopically mounted elements one associated with said supporting member and operable for imparting pivotal movement 35 thereto, and means forming a part of said bearings for holding said member in adjusted position.

7. In a portable drill rig, the combination of a carrying frame, bearings carried by said frame, a tool supporting frame, a drill carried by one end 40 portion of said supporting frame, the other end portion of said supporting frame being pivotally connected to said carrying frame by said bearings, and a mechanism carried by one of said bearings associated with said tool supporting frame for 45 normally preventing the pivotal movement thereof, said mechanism being selectively operable for imparting pivotal movement to said supporting frame.

8. In a portable drill rig, the combination of a 50 carrying frame including two side arms, an individual connecting member carried by each of said side arms, a bearing within each of said connecting members, a tool supporting frame pivotally connected to said carrying frame by each of said 55 bearings, and a mechanism including a duality of telescopically mounted elements one pivotally connected to one of said connecting members above said bearing and the other pivotally connected to said supporting frame, said mechanism 60 being operable for imparting pivotal movement to said supporting frame.

9. In a portable drill rig, the combination of a carrying frame including two side arms, an individual connecting member carried by each of said 65 side arms, a bearing within each of said members, a tool supporting frame having a drill carried by one end portion thereof, the other end portion of said supporting frame being pivotally connected by said bearings to said carrying frame, and a 70 mechanism including a duality of telescopically mounted elements one connected to one of said connecting members and the other connected to said supporting frame near the drill carrying end portion thereof, said mechanism being operable 75

for imparting pivotal movement to said supporting frame.

10. In a portable drill rig, the combination of a carrying frame including two side arms, a connecting member carried by each of said side arms, a bearing within each of said members, a tool supporting frame having a drill carried by one end portion thereof, the other end portion of said supporting frame being pivotally connected to said

5 carrying frame by said bearings, a brace between one of said connecting members and the drill carrying end portion of said supporting frame, said brace normally preventing the pivotal movement of said supporting frame, and means operable for 10 selectively varying the length of said brace, imparting thereby pivotal movement to said supporting frame.

11. In a portable drill rig, the combination of a carrying frame including two side members, an individual connecting element carried by each of

15 said side members, a bearing within each of said connecting elements, a tool supporting frame pivotally connected to said carrying frame by each of said bearings, and a mechanism carried by one of said connecting elements associated with said tool supporting frame for normally preventing the pivotal movement thereof, said mechanism being operable for imparting pivotal movement to said supporting frame.

12. In a portable drilling rig, the combination of a carrying frame including two side members, a connecting element carried by each of said side members, a tool supporting frame pivotally connected to said carrying frame by said connecting elements, a mechanism carried by at least one of said connecting elements associated with said tool supporting frame for imparting pivotal movement thereto, and means for locking said frames against pivotal movement.
